UNITED STATES PATENT OFFICE.

HERBERT E. WHITE, OF YOUNGSTOWN, OHIO.

COATING PROCESS FOR BUILDING MATERIAL.

1,302,260.

Specification of Letters Patent. Patented Apr. 29, 1919.

Application filed September 9, 1915. Serial No. 49,757.

To all whom it may concern:

Be it known that I, HERBERT E. WHITE, a citizen of the United States, residing at Youngstown, in the county of Mahoning and 5 State of Ohio, have invented certain new and useful Improvements in Coating Processes for Building Material, of which the following is a specification.

This invention relates to the manufacture 10 of composite building material available chiefly for lathing, and primarily has for its object a process of developing and placing upon the paper or fibrous base an artificial stone composition which gives stability 15 and strength to the material, as well as imparting thereto fire-resistant and water-repellent characteristics.

The general object of the invention is to 20 commercialize the manufacture of paper lath products, whereby the same can be made with economy and rapidity by means of mechanical instruments. To that end, a distinctive feature of the present process resides in a novel step of coating the fibrous base or 25 paper body with an artificial stone composition. In this connection, the invention has in view two important objects. First, to apply the coating composition so that it will thoroughly cover and impregnate the fibrous 30 base or body. Second, to utilize, as a part of the coating operation chemicals having certain required characteristics, in combination with a novel atomizing action that has the effect of producing the artificial stone composition at and on the fibrous base during 35 its transit through the coating outfit or machine.

A further object of the invention is to 40 follow the coating operation with a supplementary step whereby the stone-coated material may be provided with a sanded bonding-surface which contributes materially to the strength of the material, as well as providing a better bond for the plaster.

45 With these and other objects in view, the invention consists in the novel process steps hereinafter explained and claimed, and while various instrumentalities or devices may be employed to assist in performing the operations to carry these steps into effect, one 50 form of apparatus that may be utilized for that purpose is shown in the accompanying drawings, in which—

Figure 1 is a longitudinal sectional view 55 of a coating outfit for carrying out the present invention.

Fig. 2 is an end elevation of the coating outfit or machine.

Fig. 3 is an enlarged detail sectional view 60 of one type of spray nozzle that may be used for effecting the chemical combination between the separate ingredients of the coating 65 composition, and the application of the resultant substance to the fibrous body or paper sheet.

Similar reference characters designate corresponding parts throughout the several figures of the drawings.

As above indicated, a distinctive and important feature of the present invention resides 70 in spraying the fibrous base or paper sheet, during its course of manufacture into a paper lath product, with a coating composition having the character of artificial stone, and to develop the latter at the time of its 75 application. That is to say, according to the principles underlying the invention, the final mixing and reunion of the ingredients of the coating emulsion or paste occurs in the act of projecting the same onto the fibrous base. 80 To render this effective and practical, it is intended to select ingredients which may be chemically united in connection with a high temperature fluid and preferably in the open air, so that when this fluid is utilized to 85 atomize and combine the said ingredients, an artificial stone composition results during the atomizing action, and it is this stone composition which is applied to the base at the time of its formation. Various chemicals 90 having these characteristics may be utilized for the purpose, but it is found preferable to employ for the coating emulsion or paste a mixture of silicate of soda and carbonate of calcium, the carbonate of 95 calcium being of course finely ground and conveniently being that material which is commonly known and sold as whiting or powdered chalk.

A mixture of silicate of soda and carbonate of calcium is specially desirable and available for the purposes of the present invention because of the capacity of such mixture to dry upon exposure to the air, and, if heated to about 200° Fah. for a brief period, 100 to become practically insoluble in water at ordinary temperature. In other words, the product resulting from the chemical union of silicate of soda and carbonate of calcium, 105 brought about by the application of heat thereto while in a finely divided state and in the presence of air, is an artificial stone 110

that satisfactorily fulfills the requirements as a coating for paper lath products.

In order to bring about the proper chemical union between the ingredients of the coating emulsion or paste at the time of application to the fibrous body or paper sheet requires a device or instrument capable of breaking up the mixture into a finely divided state, and at the same time supplying 10 the necessary heat and oxygen for the reaction. This operation may be successfully performed by utilizing, in a suitable coating machine or outfit, spray nozzles N having the structural and functional characteristics 15 of the nozzle illustrated in detail in Fig. 3 of the drawings.

Referring briefly to the illustrated form of spray nozzle, it will be observed that the same includes in its general organization, 20 an outer nozzle member 1 and an inner nozzle member 2 concentrically arranged in spaced relation to leave an interior ejecting-fluid chamber 3 which is in communication with a source of steam or hot-air supply 25 through the ejecting-fluid supply pipe 4. The inner nozzle member 2 is formed with an interior suction chamber 5 which is in communication with the source of supply for the coating emulsion or paste through 30 the paste supply pipe 6. Both of the nozzle members are provided with concentrically arranged conical discharging heads 7 and 8 arranged one within the other and provided with the jet orifices 9 and 10 respectively, 35 while between the points of these heads there is provided a narrow annular blast passage 11 through which the steam or hot-air under pressure discharges at high velocity. The extent of opening permitted 40 through the jet orifices 9 and 10 may be regulated through the medium of a suitably mounted regulating valve or mandrel 12, whose reduced extremity 13 is arranged to be projected more or less into the said orifices. 45 With a nozzle constructed as described, it will be obvious that the steam or hot-air under pressure, issuing through the blast passage 11 and the outer jet orifice 10, creates a partial vacuum within the suction 50 chamber 5 of the inner nozzle member, thereby drawing the emulsion or paste in and through the inner nozzle and atomizing the same as it emerges therefrom. The steam mixes with the finely divided paste 55 and sprays the same onto the object to be coated, at the same time supplying the necessary elements to convert the mixture into the artificial stone composition.

A feature of the process also resides in 60 causing the newly-formed stone composition to be applied to the paper body or sheet at the time of the atomizing action referred to, and while this may be accomplished in various ways and with different mechanical devices, one way of carrying out this phase of

the process is illustrated by the coating outfit or machine shown in Figs. 1 and 2 of the drawings, and which outfit or machine includes spray nozzles having the functional characteristics above explained.

In explanation of the coating outfit or machine shown in the drawings, it will be observed that the same includes a supporting frame or bed 14 having mounted thereon a suitable housing 15 open at both ends to permit of the continuous passage therethrough of the fibrous base or sheet which is to be manufactured into a stone coating paper lath product. This material is propelled through the housing by means of a plurality of interior roll units 16 and the exterior roll units 17 and 18, the latter roll units being located respectively at the feeding and delivery ends of the chamber. All of these roll units preferably comprise an axle member 18^a and a plurality of spaced tractor disks 19 whose peripheries have a frictional engagement with the sheet S for moving the latter continuously, or intermittently, if desired, through the machine. 85 The tractor disks of the interior units have their peripheries project through slits 20 in arched shield plates or guards 21 which serve to protect the disks and the shafting from the fluids and paste. Furthermore, 90 these shield plates or guards 21 are shown arranged to provide waste-conserving chutes 22 and 23, respectively for the surplus or excess paste and sand which may fall from the sheet S being treated. The chute 22 for the paste is illustrated as having a return pipe connection 24 with a paste supply receptacle 25, while the chute 23 is shown as being provided with a return pipe connection 26 with a sand supply box 27.

A transverse series of the paste spray nozzles N are preferably arranged both above and below the sheet S to be treated so that the upper series of nozzles N spray the stone composition onto the upper side 110 of the sheet, while the lower series of said nozzles spray the said composition onto the under side of the sheet. And, as the said sheet is usually provided with keying slots or openings for the plaster, the plastic composition is permitted to thoroughly envelop and penetrate the said sheet. The paste supply pipes 6 for the lower nozzles N enter the paste supply receptacle 25, while the corresponding pipes of the upper nozzles N enter 115 an upper separate paste supply receptacle 28.

A further feature of the invention relates to the sanding step which is supplementary to the primary coating step. This supplementary step is intended to provide a sand surface for the product which insures additional protection for the surface thereof while being handled and applied, while at the same time affording a better bond for the 120 125 130

plaster when applied to the lath. In connection with this sanding step, it will be observed that the adhesive stone coating which is manufactured and applied by the 5 atomizing nozzles will still be in a plastic or undried condition when the sheet reaches the sanding zone, so that the said coating will answer the additional purpose of holding the sand in place until the entire structure has dried and set.

The application of the sand may be conveniently made by the use of sand blast nozzles N' arranged respectively above and below the plane of the sheet feed. These 15 sand blast nozzles are in communication with a source of ejecting-fluid supply, as compressed air, through the pipes 29, and with a source of sand supply through the pipes 30. The pipes 30 for the lower sand 20 blast nozzles enter the sand supply box 27, while those for the upper sand blast nozzles enter the sand supply box 31.

From the foregoing, it is thought that the important feature of the invention involved in the primary coating operation and 25

the production of the stone composition at the time of its application will be well understood without further description, but in this connection it will also have been observed that the supplementary step of sanding is an important and practical feature of the invention, since the two steps coöperate to provide an improved and commercial form of paper lath product.

I claim:

1. A coating process of the class described which consists in consolidating with a fibrous body, by atomization, a hot mixture of stone-forming materials.

2. A coating process of the class described 40 which consists in consolidating with a fibrous body, by atomization under pressure, a hot steam-saturated mixture of silicate of soda and carbonate of calcium.

In testimony whereof I hereunto affix my 45 signature in the presence of two witnesses.

HERBERT E. WHITE.
